UNITED STATES PATENT OFFICE.

ORA OSTRANDER AND HIRAM H. FAIRCHILD, OF GRAND RAPIDS, MICHIGAN.

DESIGN FOR A KITCHEN-CABINET.

SPECIFICATION forming part of Design No. 25,080, dated January 21, 1896.

Application filed September 30, 1895. Serial No. 564,240. Term of patent 7 years.

To all whom it may concern:

Be it known that we, ORA OSTRANDER and HIRAM H. FAIRCHILD, citizens of the United States, residing at Grand Rapids, in the county 5 of Kent and State of Michigan, have invented and produced a new and original Design for a Kitchen-Cabinet, of which the following is a specification, reference being had to the accompanying drawing, showing a part thereof.

10 We show in the accompanying drawing a perspective of our cabinet, the same being deemed sufficient to illustrate our design fully.

Our design consists of the general construction, as shown in the drawing, the main features being the lower portion or table A, having closet M for any desirable purpose; a series of drawers G and G' disposed in the front of the case, substantially as shown; a 15 flour-bin II and a bread-board I inserted in the case at the side of the bin, and an opening J between the drawers G' and flour-bin. This case has a metallic cover C provided with a narrow upwardly-projecting rim c. 20

25 The second feature of our design consists

of an upper case B. This case is provided with a set of drawers F on each side and a row of smaller drawers E across the top. Crown- 30 ing this opening is an ornamental cornice L'. The back portion of the top C under the two sets of drawers F is made plain and level with the rim c to support the case B, and the portion between the two sets of drawers F is formed into a deep basin C'.

What we claim is—

35 The design for a kitchen cabinet substantially as herein shown and described.

Signed at Grand Rapids, Michigan, this 28th day of August, A. D. 1895.

ORA OSTRANDER.

HIRAM H. FAIRCHILD.
